UNITED STATES PATENT OFFICE.

CHARLES A. ISBELL, OF PASADENA, CALIFORNIA, ASSIGNEE OF ONE-HALF TO WILLIAM H. MILLER, OF LOS ANGELES, CALIFORNIA.

THEFT ALARM.

Application filed February 5, 1920. Serial No. 356,468.

To all whom it may concern:

Be it known that I, CHARLES A. ISBELL, a citizen of the United States, residing at Pasadena, in the county of Los Angeles and State of California, have invented new and useful Improvements in Theft Alarms, of which the following is a specification.

This invention relates to theft alarms for vehicles and particularly to automobiles, and has for its object to provide a device of this kind that is simple in construction, is reliable, can readily be installed in combination with the usual ignition circuit of motor driven vehicles, and that is key controlled; and the invention consists of the construction, the combination and in details and arrangements of the parts an embodiment of which invention is illustrated in the accompanying drawings and described and claimed herein.

Figure 1 is a plan or top end view of the device partly in section.

Fig. 2 is a sectional view on line 2—2 of Fig. 1.

Fig. 3 is a sectional view on line 3—3 of Fig. 2.

Fig. 4 is a diagrammatic view of the wiring in the apparatus.

The invention comprises the organization, in combination with the usual ignition circuit of a motor driven vehicle, of a signal device that may, and preferably does, consist of a bell or other audible alarm means with means designed to so set elements in the apparatus that upon the closing of the ignition circuit controlling switch without the manipulation of the parts by the use of a proper key there will then be given a signal to attract attention to the attempted starting of the motor.

The apparatus is capable of being attached as a unit at any desired position upon the vehicle structure and in such location that it can be readily accessible to those familiar with the location for the insertion of a controlling or operating key.

In its illustrated form, the invention includes a suitable receptacle or box 2 having a cylinder lock 3 to be turned by a complementary key 4 the cylinder of the lock having a lever or contact blade 5 arranged within the box 2 and which when turned in one position, as shown in Figs. 2 and 4, is designed to engage with insulated contacts

6 and 7. The contact 6 is shown as connected by a wire 8 to a line 9 which is broken at 10 and is provided with spaced contacts 11 and 12, the latter contact being connected to a wire 13 shown as extended to an induction coil 14 which is connected in turn to one contact post of a main or ignition circuit switch 15. This switch is connected by a wire 16 to a source of current, indicated here as a battery 17, which is grounded as at 18. From the contact 7 there is extended a wire 19 which is connected to the motor M forming a part of the ground 18.

It will therefore be seen that when the switch blade 5 is turned to complete the circuit at the contacts 6—7 current will flow, when the switch 15 is closed, from the battery 17 and switch 15, through coil 14, line 13 to the contact 12 which is insulated from the contact 11 and for the completion of the circuit at the gap 10 there is provided a reciprocating rod 20, in this case, having its upper end adapted to engage the co-ordinate contacts 11—12.

The contact rod 20 is provided with a member in the form of a disc 21 which is shown in Fig. 2 as engaged by a pin or dog 5^a attached to a part of the cylinder lock, as on the blade 5. Therefore, the lock cylinder has the dual function of closing the circuit at 6—7 and also lifting the contact rod 20 in one operation so that when the circuit is closed at the contacts 11 and 12 the circuit will then be completed through the lines 9—8, contacts 6—7 and line 19 to the motor to supply current to the igniting apparatus of the system including the usual spark plugs not shown.

The operator of the vehicle desiring to leave the same may insert the key 4 in the lock 3 and turn the cylinder so as to break the circuit by withdrawing the contact blade 5 from the contact 6—7 and turn the blade until it will engage co-ordinate contact members 22 and 23, the latter being connected to the ground while to the contact 22 there is attached a wire 24 connected to one terminal of a solenoid coil 25 from the opposite terminal of which there extends a wire 26 which is shown as tapped into the line 9.

Since the contact member 20 has been left in frictional engagement with the co-ordinate contacts 11 and 12, a circuit therefore will pass through the coil 25 to line 9 across

the contacts 11, 20 and 12 and to line 13 through the coil 14, and if the switch 15 be closed, through line 16 to the battery 17 so that the coil will be energized and the rod 20 which forms a core in the coil 25 will be retracted so that the circuit is broken at the contacts 11-12.

Upon the retraction of the solenoid core 20 the disc 21 is brought down to contact with suitably arranged contact members 26 and 27. These contact members may be mounted on and insulated from the coil 25. The contact 26 is connected to a wire 28 tapped into the line 16, and the contact 27 is grounded as at 29. In the line 28 there is arranged any suitable electrical or electromagnetic signal device, in the present case, shown as comprising an electric bell 30.

From the above it will be seen that after the switch 5 has been turned by the key 4 to close the circuit at the contacts 22-23 the coil 25 will be energized while the switch 15 is still closed and the circuit will then be broken at 11-12 by the retraction of the circuit closing member 20, and at the same time the alarm circuit will be completed by the engagement of the member 21 with the contacts 26-27 and an alarm established by the energization of the signal device 30. The operator then simply breaks the circuit, if not open, at the ignition circuit switch 15 by opening the same.

Any person then who attempts to start the motor by closing the ignition circuit switch 15 will in consequence give the alarm by the device 30 and this can only be prevented by the insertion of a proper key into the lock so as to break the bell circuit by lifting the contact member 21 from engagement with the bell circuit contact.

Various changes may be made without departing from the spirit of the invention as claimed.

What is claimed is:

1. The combination, with an internal combustion engine ignition circuit having a main ignition switch and three additional switches, two of which are in the ignition circuit, of a key-controlled means for alternately opening and closing one of said switches and the third switch, a solenoid in said circuit having a core provided with means for opening the circuit at one of the switches in the ignition circuit when energized, said switch including means for keeping the circuit closed thereat when the solenoid is de-energized, a shunt around the solenoid including the third switch, and means operative by the key-controlled means for moving the solenoid core operated means to circuit-closing position on the movement of the third switch to circuit-closing position.

2. The combination, with an internal combustion engine ignition circuit having a main ignition switch and three additional switches, two of which are in the ignition circuit, of a key-controlled means for alternately opening and closing one of said switches and the third switch, a solenoid in said circuit having a core provided with means for opening the circuit at one of the switches in the ignition circuit when energized, said switch including means for keeping the circuit closed thereat when the solenoid is de-energized, a shunt around the solenoid including the third switch, means operative by the key-controlled means for moving the solenoid core operated means to circuit-closing position on the movement of the third switch to circuit-closing position, an alarm, a normally open alarm circuit, and means operated by the solenoid to open the ignition circuit and to close the alarm circuit.

In testimony whereof I have signed my name to this specification.

CHARLES A. ISBELL.
